APPARATUS FOR DISENGAGING GEAR TEETH OF POWER DRIVEN RAILWAY TRUCKS

Jesse F. Holloway, Aldan, Pa., assignor to The Baldwin Locomotive Works, a corporation of Pennsylvania

Application November 5, 1941, Serial No. 417,910

3 Claims. (Cl. 105—136)

This invention relates generally to locomotives and more particularly to those employing an electric motor for driving an axle through a pinion and gear.

Electric motors employed in locomotives of the Diesel electric type or of the all electric type drive the axles through gears whose teeth occasionally break thus requiring removal of the locomotive to a round house for repairs. Heretofore considerable difficulty has been encountered in returning a locomotive to the round house because the gear teeth become jammed upon breakage of a tooth. It is particularly desirable to have the locomotive travel under its own power through the remaining motors and gears which are in good condition but this has been difficult because of the jammed teeth. On the other hand, the wheels associated with the broken gears have at times been skidded along the track but this merely causes a flat spot to be worn on the jammed wheel and accordingly aggravates the repair work to be done. Furthermore, such skidding practice requires taking another locomotive out of active service for towing away the disabled locomotive. To avoid these difficulties it has been customary either to burn off the armature shaft or split the gears in order to disengage the pinion, this of course being costly to the railroad as well as tying up the trackway for a long period of time inasmuch as the operation is performed at the point where the locomotive is stalled.

It is an object of my invention to provide improved means whereby a locomotive may be returned to a desired destination preferably under its own power without aggravating the damage already done to a wheel whose driving gears are broken.

A further object is to provide improved means whereby the pinion and driven gear of any damaged gear set may be rendered completely inoperative in a simple, direct and effective manner by a locomotive crew at the time the damage occurs so that the locomotive may then be returned to its desired destination or round house preferably under its own power.

A still further object is to provide improved means adapted to utilize, as a cooperative part of my improved combination, existing truck and motor structure to separate the motor pinion from the axle gear and maintain the same in separated relation during travel of the locomotive to the round house or other destination.

Other objects and advantages will be more apparent to those skilled in the art from the follow-

ing description of the accompanying drawings in which:

Fig. 1 is a side elevation of a truck partially broken away to show my improved gear disengaging means;

Fig. 2 is a transverse section taken substantially on the line 2—2 of Fig. 1;

Fig. 3 is a fragmentary section of a complete motor bearing journaled upon a driving axle;

Fig. 4 is a fragmentary plan view of one end of a truck frame with my gear separating means attached thereto, this view being taken substantially at the position of line 4—4 of Fig. 1; and

Fig. 5 is an enlarged section showing my improved means applied to the motor housing for disengaging gears and for supporting the motor housing in the disengaging position during transit.

While I have shown my invention as applied to one form of electric truck, it will of course be understood that my invention may be employed on various other forms and types of trucks. In the particular truck herein disclosed, I have shown a pair of wheels 1 mounted upon axles 2 and journaled in usual journal boxes 3 which in turn are supported in pedestals of a suitable truck frame 4. This frame may be supported upon any suitable spring suspension system specifically shown herein as having longitudinal springs 5 supported upon an equalizing beam 6 which, as is customary, has its ends seated upon the journal boxes 3. A usual bolster 7 of the rigid type is suitably supported upon the spring system between side wheel pieces 4 of the truck frame although other types of bolsters may be employed. The side wheel pieces are connected at their ends by usual end sills 8. As is customary, the axles are provided with gears 9 driven by an electric motor 10 through a pinion gear 11. The electric motor is journaled, as shown in Figs. 3 and 4, upon the axle 2 through a pair of transversely spaced journal bearings 12 and 13 which, as shown in Fig. 3, have usual bearing caps 14 removably secured to the motor frame by bolts 15 and cap screws 16. The motor torque is resisted by a pair of usual motor arms 17 engaging an intermediate spring cushion arrangement consisting of a pair of bars 18 between which compression springs 19 are disposed. The cross bars 18, in turn, rest against the inner horizontal sides of two bolster arms 20 and 21. Regardless of the direction of motor rotation the torque is adequately resisted and cushioned.

To accomplish my improved result of disconnecting the pinion in a simple, direct and effec-

tive manner, I propose to bodily shift the entire motor structure and its pinion away from meshing engagement with the axle gear and at the same time rigidly support the motor in its shifted position while the locomotive travels under the power of its remaining motors if possible. In performing these functions I have not only provided extremely simple and rugged elements but also have brought the same, in the illustrative embodiment herein, in cooperative relation to existing truck frame and motor elements. For instance, as shown in Figs. 1 and 5, a supporting arm 24 having a preferably inverted U-shaped clamp portion 25 is secured temporarily if desired by a set screw 26 or permanently by welding to or casting with the end sill 8 of the truck frame. The arm 24 is heavy and rugged and is provided at its lower end with a recess 27 in which a bolt 28 is rotatably seated. The outer end of this bolt is threadedly received in a bracket 29 which is bolted to the upper ears 30 of the motor bearing. As shown in Fig. 4, the bracket 29 is as wide as the motor bearing and is provided with holes which register with the motor holes for bolts 15. Hence it is possible to utilize the same bolts 15 as are normally used for holding the motor bearing cap 14. Each of the motor bearings 12 and 13 are provided with one of the foregoing brackets and arms 24 and hence the description of one will suffice for both.

Operation.—When a gear becomes damaged the locomotive crew will first remove bolts 15 and cap screws 16 from both axle motor bearings 12 and 13 and then secure the supporting brackets 24 to the end sill 8 in case the brackets are of the removable type. The bolts 28 will then be inserted into the recesses 27 and the bracket 29 will be secured by bolts 15 to the upper ears 30 of the motor bearings. The bolts 28 will then be rotated by applying a wrench to bosses 31, Fig. 5, formed integrally with bolts 28 thereby bodily moving the motor 10 upwardly and inwardly until pinion 11 is disengaged from gear 9. During this inward movement of the motor it will be slightly supported by ears 17 on the cross bars 18 and arms 21 of the torque cushion. When the pinion and gear are sufficiently separated it may be locked by a nut 32, Fig. 5. The locomotive will now be in condition to travel on its remaining motors without danger to further damaging the gears or other mechanism of the disabled wheel assembly. It will of course be understood that any usual gear case diagrammatically indicated at 33, Fig. 4, will be removed or suitably disconnected to permit separation of the pinion and gear. Also, if desired, the cushion spring pressure on motor suspension bars 18 may be relieved by screwing up on bolts 22 Fig. 2 thus permitting easier shifting of the motor.

From the foregoing disclosure it is seen that I have provided an extremely simple, direct and rugged combination of elements for allowing a disabled motor to be easily and quickly disconnected without unduly delaying traffic on a roadway. The device is not only simple but is economical and compact and hence can be made an effective part of regular equipment of each locomotive. Furthermore, my improved arrangement requires minimum disconnection or removal of regular parts of the locomotive or motor equipment and this is accomplished in part by reason of having effectively imposed multiple functions on existing parts.

It will of course be understood that various changes in details of construction and arrangement of parts may be made by those skilled in the art without departing from the spirit of the invention as set forth in the appended claims.

I claim:

1. In combination, a truck having a frame mounted upon wheeled axles, a motor having journal bearings mounted on one of said axles to support one end of said motor, a motor pinion, gearing between said pinion and axle upon which said motor is mounted, said journal bearings being in separable sections whereby the motor may be moved laterally with respect to the axle to effect disengagement of said pinion and gearing, an element of variable length, means for securing one end of said element to said motor, and means for securing the other end of said element to said frame, said element extending in a direction whereby variation of said length moves said motor to a position for disengaging said pinion and immovably holds the motor in its disengaged position.

2. The combination set forth in claim 1 further characterized in that said variable length element comprises a screw and nut one of which is secured to said motor and the other to said frame in a substantially single angular position with respect to the motor and frame whereby upon relative rotation between the nut and screw the motor is bodily shifted to a disengaged position and held in that given disengaged position.

3. The combination set forth in claim 1 further characterized by the provision of a member projecting from said frame to a point in common alignment with said motor, which alignment is in the direction of disengaging movement of the motor, and said element including a nut and screw interposed between said member and motor so that said screw is subjected to compression upon relative rotation between the nut and screw to effect said disengagement whereby said motor is firmly held in its disengaged position by the compressive force in said screw.

JESSE F. HOLLOWAY.
